UNITED STATES PATENT OFFICE.

ROBERT GORDON WILLIS, OF LONDON, ENGLAND.

GRAMOPHONE AND LIKE TALKING MACHINE.

Application filed July 6, 1925. Serial No. 41,754.

To all whom it may concern:

Be it known that I, ROBERT GORDON WILLIS, a subject of the King of Great Britain, residing at 2 and 3 Newman Street, W. 1, 5 in the county of London, Kingdom of England, have invented certain new and useful Improvements in or Relating to Gramophones and Like Talking Machines, of which the following is a specification.

10 This invention refers to improvements in or relating to gramophones and like talking machines, and it has for its object to simplify their construction by providing, in combination therewith, an improved brake 15 which is adapted to be actuated by the moving into position of the sound-box and needle by hand, the arrangement being such that the placing of the needle on the record causes the motor to be started, whilst the 20 turning up of the sound-box and the removal of the needle from the record causes the motor to be stopped. The invention is distinguished from apparatus in which a sound-box is raised from the record and 25 the motor is stopped by the operation of a crank handle or a slideable rod.

Thus, according to the present invention, I provide, in combination with a gramophone or like talking machine, brake mechanism 30 adapted to be actuated to stop the motor and/or the turntable when the sound-box and needle are lifted directly by hand and from the record.

In order that the present invention may 35 be clearly understood and more readily carried into effect, it is hereinafter described with reference to the accompanying drawings, in which:—

40 Figure 1 is a partly sectional side elevation of part of a gramophone illustrating the application thereto of the present invention;

Figure 2 is an end elevation thereof.

45 Figure 3 is a detail sectional elevation of the brake disc;

Figure 4 is an inverted plan view illustrating the method by which the stop member of the Bowden brake mechanism is secured to the base portion of the tone-arm, 50 and

55 Figure 5 is an enlarged partly sectional detail view of the horizontal socket piece at the joint of the tone-arm connecting with the sound box, illustrating the method of securing the pin or lug to the brake-actuating mechanism.

As shown, and in carrying the present invention into effect, the sound box *a* and tone-arm *b* may conveniently be of the conventional swan-neck type, the sound-box *a* 60 being mounted at one end of a U-shaped extension *b'* of the tone-arm *b* which is adapted to rotate in a horizontal socket-piece *b*² at right angles to the axial line of the tone-arm proper *b*. In this construction 65 the inner end of the U-shaped tone-arm extension-piece *b'* is provided with an eccentrically disposed pin or lug *c* to which the inner end of a brake-actuating mechanism or wire *d* is suitably connected, the said 70 brake-actuating mechanism or wire *d* conveniently passing down the tone-arm *b* into and out of the amplifier and below the top board *f* of the motor *g*, to a suitable spring-controlled brake member *h*. Conveniently 75 the brake-actuating mechanism may comprise a suitable length of Bowden mechanism *d*, *d'*, the inner and inextensible member *d* of which is connected at one end to the pin or lug *c* on the U-shaped tone-arm 80 extension piece *b'*, whilst the other end is connected to the aforesaid spring-controlled brake member *h*, the outer member *d'* of the Bowden mechanism being connected to suitable stops or abutments *e*, *e'* within the tone-arm *b* and on the casing of the motor *g*, 85 respectively.

At the brake end proper the brake member *h* may conveniently be adapted to operate directly with a disc *i* provided in 90 connection with the motor governor *j*, or, as shown, with a more or less resilient stop *k* on a spring washer or member *k'* working in a circumferential groove in said disc *i*, whilst the whole fitting at the motor end 95 may be conveniently mounted on a bracket plate or member *l* adapted to be suitably screwed or bolted on to the motor casing *g*. In some cases the brake may operate on the turntable as heretofore. The arrangement 100 of the brake is such that when the sound-box *a* is lowered into a position where the needle engages the record *m*, the spring *o* of the brake mechanism will cause the withdrawal of the brake member *h*, thus permitting the 105 governor *j* and the motor and turntable *n* to rotate. As soon, however, as the sound-box is turned back into a position for inserting a fresh needle the brake member *h* returns against the influence of its spring *o* 110 and stops the motor and the gramophone turntable.

In the particular construction illustrated in Figure 5 the pin or lug *c* to which the end of the inextensible Bowden cable *d* is connected, is secured to a cone or wedge-shaped disc *p* which is placed within the inner portion of the extension member *b'* and held securely in place by means of a screw *q* which passes through the end disc of a longitudinally split cup *r*, the arrangement being such that the tightening of the said screw *q* causes the split cup *r* to be extended tightly against the inner circumference of the member *b'*. Thus both the member *r* and the conical disc *p* are held firmly in place and the wire *d* passes out through slots *s* and *t* provided in the extension member *b'* and the socket *b²*, respectively.

It will thus be seen that by the present invention I am enabled to provide an extremely neat and simplified arrangement wherein not only is the starting and stopping of the turntable effected by the positioning of the needle on, and its removal from, the record but wherein the brake for effecting this starting and stopping may if desired be arranged in connection with the motor mechanism, so that the top of the motor case around the turntable may be quite plain except for the turntable and the tone-arm and speed indicator.

What I claim is:—

1. An automatic braking mechanism for

gramophones, comprising a flexible wire support having one end terminating at the base of the tone arm and extended therefrom through and beyond the amplifying horn to the motor mechanism, a brake arranged for cooperation with the motor mechanism, a flexible wire leading from the brake through said connection and lengthwise the tone arm to the sound box extension, and means whereby said flexible wire may be operated to actuate the brake in movement of the sound box extension in one direction.

2. A brake operating flexible connection for gramophones or the like, and means for actuating said connection in the movement of the sound box extension, said means comprising a disc seated in the bearing part of said sound box extension and having an eccentric pin to receive one terminal of the flexible connection, a cap for closing the sound box extension and having a slotted flange to seat within the open end of such extension, and a threaded pin mounted in the cap and having operative connection with the disc to draw the latter into the flange for the spreading of the flange into frictional engagement with said extension to hold the disc against movement.

In testimony whereof I have hereunto signed my name.

ROBERT GORDON WILLIS.
